United States Patent Office

Des. 180,583
Patented July 9, 1957

180,583

STAND FOR A TELEVISION PROGRAM OR THE LIKE

Eva Z. Craig, Seattle, Wash.

Application February 27, 1956, Serial No. 40,329

Term of patent 7 years

(Cl. D33—3.1)

Fig. 1

Fig. 2

Fig. 1 is a front perspective view of a stand for a television program or the like, showing my new design; and

Fig. 2 is an edge elevational view thereof.

The characteristic features of my design are shown by means of full lines in the drawing.

I claim:

The ornamental design for a stand for a television program or the like, as shown and described.
